UNITED STATES PATENT OFFICE

167,594

HAND CONTROL FOR DICTATING MACHINES

Ralph A. Sherman, Jr., Fairfield, Conn., assignor
to Dictaphone Corporation, Bridgeport, Conn.,
a corporation of New York

Application January 31, 1951, Serial No. 14,053

Term of patent 14 years

(Cl. D26—13)

To all whom it may concern:

Be it known that I, Ralph A. Sherman, Jr., a citizen of the United States, residing in the town of Fairfield, in the county of Fairfield, and in the State of Connecticut, have invented a new, original, and ornamental Design for a Hand Control for Dictating Machines, of which the following is the specification, reference being had to the accompanying drawings, forming part thereof.

Figure 1 is a perspective view of a hand control for dictating machines looking toward the left-front corner thereof, showing my new design;

Figure 2 is a front elevation thereof;

Figure 3 is a top plan view thereof; and

Figure 4 is an elevation of the right-hand side thereof.

The elevation of the left-hand side of the hand control for dictating machines shown in Figure 1 appears the same as the elevation shown in Figure 4.

The back and bottom surfaces of the hand control for dictating machines shown in Figure 1 are plain.

I claim:

The ornamental design for a hand control for dictating machines, substantially as shown and described.

RALPH A. SHERMAN, JR.
